[57] CLAIM

The ornamental design for a headphone, as shown and described.

DESCRIPTION

FIG. 1 is a perspective view of a headphone showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view of an alternate embodiment of FIG. 1;

FIG. 9 is a top plan view of FIG. 8;

FIG. 10 is a left side elevational view of FIG. 8; and,

FIG. 11 is a right side elevational view of FIG. 8.

The undisclosed rear and bottom views of the alternate embodiment are the same as FIGS. 3 and 5 respectively.
